CONCRETE BLOCK MOLDING MACHINE

Alf G. Carlsen, Tacoma, Wash.

Application August 6, 1946, Serial No. 688,755

8 Claims. (Cl. 25—41)

1

This invention relates to concrete block making machines and is particularly adapted for making concrete blocks.

The primary object of the invention is to form concrete blocks by precision forms so that the final block will be a precision made block.

A further object of the invention is to provide a form having one of its side walls retractable from the blocks formed therein so that the blocks can be moved out through the form without disfiguring said blocks.

A still further object of the invention is to provide sub-forms for shaping the blocks within the overall form.

A further object of the invention is to provide a means of moving the sub-forms, including the moulded blocks, out of the overall form replacing said sub-forms with additional forms ready for forming the next group of concrete blocks.

Another object of my invention is to provide special shaping forms to be inserted within the sub-forms and the overall forms for making rounded corners on the blocks.

These and other incidental objects will be apparent in the drawings, specification and claims.

Referring to the drawings:

Figure 1 is a side view of my new and improved concrete block making machine.

Figure 2 is an end view of Figure 1, taken on line 2—2.

Figure 3 is a plan view of the machine.

Figure 4 is another modified form of concrete block making machine.

Figure 5 is an end view of Figure 4.

Figure 6 is a longitudinal side view, partially in section, parts broken away, taken on line 6—6 of Figure 2.

Figure 7 is a perspective view of one of the sub-forms.

Figure 8 is a perspective view of one of the concrete blocks having been formed.

Figure 9 is the same as Figure 8, except that the block has been inverted.

Figure 10 is a plan sectional view taken on line 10—10 of Figure 1, illustrating the concrete blocks being formed within the form.

Figure 11 is the same as that of Figure 10 except that the side of the master form has been retracted from the sub-forms and the concrete blocks relieving the surface friction so that the blocks can be replaced by additional forms. In this view the new forms are being brought into place forcing the forms containing the cast blocks out of the machine.

Figure 12 is an end sectional view, taken of the

2

machine on line 12—12 of Figure 1, parts broken away for convenience of illustration.

Figure 13 is a fragmentary plan view of the forms illustrating a special corner form in place.

Figure 14 is a perspective view of the said corner form removed from the forms.

Figure 15 illustrates the sub-forms removed from the machine but supporting the blocks while said blocks are setting or hardening.

10 In the drawings:

My new and improved concrete block making machine consists of a frame 1, having a sub-frame 2 mounted upon the frame 1 by resilient blocks 3 of any well known construction. By 15 mounting the sub-frame 2 on the frame 1 by resilient blocks 3 a movement between the frame 2 and the frame 1 may be created by a vibrating mechanism, which will be described later.

20 Fixedly secured to the sub-frame 2 is an upwardly extending wall 4 forming one side of the master mold. This wall is solidly connected to the sub-frame 2 by bolts 4' or any other suitable method. Oppositely disposed from the wall 4 is a movable wall 5. This movable wall 5 has a base 6 extending therefrom and over the surface of the sub-frame 2. This wall is pivotally mounted, referring to Figures 10 and 11 at 7 to the frame 2 by any suitable pivotal connection, as for instance the bolt and nut assembly 8.

25 30 A lever 9 is pivotally mounted to the sub-base 2 at 10 and has one of its ends connected to the link 11, which is pivotally mounted to the base 6 of the side 5 of the form at 12. Referring to Figure 10, it will be noted that the lever is maintaining the side wall 5 of the form parallel to the side wall 4, but that in Figure 11 the lever has been moved to retract the side wall 5 as shown, which will be described more fully later on.

35 40 Sub-molds 13 are clamped between the side walls 4 and 5, best illustrated in Figures 6, 10, 11 and 12. These molds consist of upwardly extending ends 14 and bases 15. The ends 16 of the bases of each mold fit into the notches 17 of the next mold in line, maintaining the same in alignment. Dowel holes 18 are formed on one side of the end walls 14 of the molds and cooperate with the dowels 19, forming part of the cranks 20, which are fixedly secured to the cross shaft 21.

45 50 The shaft 21 runs longitudinal of the side wall 5 and is journalled within suitable bearings 21' within the reinforcing webs 21''. The crank 22 is keyed to the said shaft 21'' and is operated by the lever 23, which is pivotally mounted to the base 6 at 24. The lever 23 has a crank arm 25

forming part thereof, said crank arm having a crank pin 26 for engaging the slot 27 within the crank 22. When the lever is raised, referring to Figure 12, the dowel pin 19 on the cranks 20 are pulled away from the holes 18 in the side of the sub-molds 13, but when the lever 23 is lowered the crank pin 26 aligns itself with the pivot point 24, holding the dowel pins 19 in contact with the holes 18 of the sub-molds preventing end movement of the same while the concrete is being poured into the molds.

A cover plate 28 is hingedly mounted to the side wall 4 of the form at 29. A crank arm 30 forms part of the cover 28 and is pivotally connected to the connecting rod 31 at 32. The opposite end of the connecting rod being pivotally connected at 33 to the lever 34, which in turn is pivotally mounted to the frame 1 at 35. The outer end of the lever having a foot treadle 36.

A spring 37 has one of its ends connected at 32 to the crank 30 and its opposite end connected to the framework of the form at 38. This spring tends to hold the cover 28 in open position, as illustrated in Figures 1, 2 and 3, but when it is desired to close the cover plate 28 the treadle 36 is pressed downwardly, which overcomes the spring 37 and moves the cover plate to the position shown in Figures 6 and 12.

A table 39 is mounted to the side wall 5 at 40 and is braced by the end walls 41 to the base 6. In order to provide vibration to the form when forming the concrete blocks a shaft 42 is journaled under the sub-frame 2 within suitable bearings 43. Off center weights 44 are keyed to either end of the shaft, and when the said shaft is revolved at a high rate of speed these weights impart a vibrating action to the frame 2, which as stated before was mounted upon resilient blocks 3 permitting this vibration.

The shaft 42 is driven by the belt 45 from the pulley 46 secured to the shaft of the motor 47. The motor 47 is mounted to a cross shaft 48 which is journaled to the frame 1 by suitable bearings 49. A double foot pedal bar 50 is also keyed to the shaft 48 and has foot treadles 51 and 52 forming part thereof. A spring 53, having one of its ends secured to the bar 50 at 54 and its opposite end to the base 55 at 56 maintains the motor in the position shown in Figure 6. This provides a slack in the belt 45 so that the pulley 46 will not drive the same, therefore when it is desired to rotate the shaft 42 the foot treadle 52 is pushed downwardly causing the motor to rotate about the shaft 48 in the direction of the arrow tightening the belt 45. When the foot is taken off the treadle the motor will return to the natural position as shown.

A conveyor chain 57 is trained about the sprocket 58 journaled within the conveyor frame 59. This sprocket is driven by the belt 60 from the pulley 61, which is keyed to the cross shaft 62, said shaft being mounted in suitable bearings 63 within the frame 1. A V-belt 64 is driven from the pulley 46 driving the shaft 62, belt 60, sheave 65 and the chain 57.

I will now describe the operation of my new and improved concrete block making machine. The sub-molds 13 are lined up on the conveyor chain 57 and are moved therealong in the direction of the arrow by the dog 66 forming part of the chain 57 on to the sub-frame 2 and between the side walls 4 and 5 of the form to the position shown in Figures 6 and 10. The lever 9 is then moved to the position shown in Figure 10 forcing the side wall 5 towards the sub-mold 13, after 75

which the lever 23 is lowered to the position shown in Figure 12, forcing the dowel pins 19 into the holes 18 in the end walls 14 of the sub-molds locking said molds in a fixed relationship to one another.

The concrete 67 is then poured into the molds as best illustrated in Figures 6, 10 and 12, at the same time the operator steps on the foot pedal 52 causing the motor 47 to drive the belt 45 and the shaft 42, rotating the counterweights 44 causing the sub-frame 2 to vibrate settling the concrete down into the forms. A straight edge is then passed over the top of the walls 4 and 5 removing the surplus concrete on to the table 39, after which the operator steps on the treadle 36, operating the lever 34, connecting rod 31, overcoming the spring 37 and closing the cover 28 down on to the concrete within the forms.

After the forms have been vibrated sufficiently to make the concrete semi-solid the vibrator is stopped by releasing the treadle 52, the cover 28 is allowed to open by the spring 37, the lever 9 is then operated to the position shown in Figure 11 allowing the side wall 5 to pivot about its point 7, retracting its opposite end as shown, at the same time the lever 23 is released allowing the dowels 19 to be removed from the sub-forms 13. By the retracting of the side wall 5 from the forms and the concrete it is possible to move both the forms and the concrete blocks in the direction of the arrow, Figure 11, on to the receiving conveyor 68, which will deliver them to any desired location.

The moving of the forms out of the sub-form and the concrete out of the master form is accomplished by placing empty sub-forms on the conveyor chain 57 and forcing them against the sub-forms contained within the master form by the action of the dog 66 of the chain pushing the empty forms forward. In order to do this the treadle 51 of the pedal bar 50, rocking the motor 47 in the opposite direction of the arrow tightening the belt 64, rotating the shaft 62, belt 60 and the conveyor chain 57 in the direction of the arrow until the new group of subforms have pushed into the form having completed forcing the blocks out through the end 69 of the master form on to the conveyor 68, after which the lever 9 will be moved to the position shown in Figure 10, closing up the master form at which time the lever 23 will lock the dowel pins 19 into the sub-forms as above described.

I have shown formed on the face of the cover plate 28 dowels for moulding the depressions 70 into the building block 71 and I have also shown depressions 72 formed within the sub-form 13 for making the dowels 73 on the building blocks.

In order to make rounded corners on the concrete blocks I have provided a filler or forming mold 74 which is inserted within the main molds adjacent the sub-molds 13, as illustrated in Figure 13.

Referring to Figures 3, 4 and 5 I have illustrated a simplified form of block making machine incorporating my new and improved mold of the same structure as that above described, but in these drawings I have eliminated the power driven agitator and the conveyors, but have substituted a foot operated concrete tamping device.

This tamping device consists of an upright frame or guide 75 secured to the frame 1 of the machine. A group of agitating plungers 76 is

slidably mounted through the guide 77 to the upright bar 75 and is supported by the cable 78 trained about the pulley 79, said cable being operated by the foot pedal 80 working in the guideway 81. In the operation of the machine the pedal 80 is released allowing the tampers 76 to tamp the concrete into the sub-molds 13. I merely illustrate the drawings in Figures 3, 4 and 5 to show that my new and improved mold can be adapted to a hand operated machine.

I have not attempted to show the concrete supplying apparatus for the mold, as this may be any suitable kind of mechanism for this purpose, such as a hopper of some sort having a means of moving the concrete into the molds of my new and improved block making machine.

I do not wish to be limited to the exact mechanical structure as shown in my drawings and described, as other mechanical equivalents may be substituted still coming within the scope of my claims.

What I claim as new is:

1. A concrete block forming machine, including a base, a mold support resiliently mounted on the base, a mold carried by the support and including a fixed side wall, a movable side wall and partitions movable between the side walls to complete the molds, a carrier for feeding the partitions longitudinally between the side walls of the mold to molding position, means for operating the carrier, means for creating an agitation of the mold support to settle the material when in the mold, including a shaft located below the mold support and cams on the shaft to contact with said mold support, a single power means for operating the carrier and the agitating means, and manually controlled means for controlling the operating means to selectively actuate the agitating means or the carrier operating means.

2. A construction as defined in claim 1, wherein the agitating means and the carrier operating means are driven by a motor mounted for swinging movement and connections between the motor and agitating means and carrier operating means for operating said parts, and wherein means are provided for swinging the motor to selectively interrupt the operation of the agitating means or the carrier operating means.

3. A concrete block forming machine, including a base, a mold support resiliently mounted on the base, means for agitating the support, a mold mounted on the support and including a side wall fixed to the support, and an opposing side wall swingingly mounted on the support and movable relatively to the fixed side wall, and a series of movable partitions in the mold, locking means carried by the movable side wall, means for operating the locking means through the movable side wall and in locking cooperation with

the end wall formations of the partitions, a carrier for feeding the partitions in aligned relation longitudinally of and between the side walls to complete the mold formation, and means for limiting the movement of the movable side wall relative to the mold formation to free the partitions with the molded material thereon for movement relative to the side walls for discharging the molded material.

10 4. A construction as defined in claim 3, wherein a manually operable lever controls the movement of the locking means for the partitions.

15 5. A construction as defined in claim 3, wherein a manually operable lever controls the movement of the movable side wall to and from mold forming relation.

20 6. A construction as defined in claim 3, wherein the movement of the movable side wall of the mold completely frees that side wall from contact from the molded material whereby to facilitate the removal of the molded material from the mold without handling.

25 7. A concrete block forming machine, including a mold composed of a fixed wall and a hinged wall, a toggle lever connected to the hinged wall to swing said wall in mold forming position and remove said wall from mold forming position, a shaft mounted on the hinged wall with lugs to operate in openings in the hinged wall whereby to hold partitions in the mold, a lever connection to rock the shaft, a hinged plate to cover the mold, a foot lever for operating the hinged plate, a pivotally mounted motor, cams for vibrating the mold, means between the motor and cams 30 for operating the latter and a foot lever connected to the motor for tilting same on its pivot to control the vibration of the mold.

35 8. A concrete block forming machine comprising a mold including a fixed side and bottom and a hinged side, a cover plate for the mold, means for vibrating the mold, means for controlling the vibrating means, including a pivotally mounted motor, a conveyor in line with the mold, means for moving the conveyor, and means for 40 45 tilting the motor on its pivot to actuate the vibrating control means and the movement of the conveyor.

ALF G. CARLSEN.
